FIG. 1

FIG. 3

UNITED STATES PATENT OFFICE

THOMAS HENRY JONES, OF WOODTHORPE, ENGLAND

TUBULAR KNITTED FABRIC

Application filed June 17, 1929, Serial No. 371,580, and in Great Britain July 21, 1928.

This invention comprises improvements in tubular knitted fabrics and has for its object to provide an improved and novel type of fabric which has the characteristics of a shogged or racked fabric.

The principal feature of the present invention consists in a tubular knitted fabric which is composed of a plurality of series of interlacing or intermeshing stitches, certain of the stitches being disposed in an opposite sense that is to say, drawn in an opposite direction to the remaining stitches and the wales formed between the stitches of one series being disposed at an angle to the wales formed between the stitches of another series.

Another feature of the invention resides in a fabric as above wherein successive stitches of one series mesh or cross progressively in successive knitted courses with another series.

A further feature consists in the provision of a knitted tubular fabric having certain of the stitches drawn in an opposite direction to the remaining stitches, wherein the entire circumference of the fabric is traversed by the component thread or threads and wherein one series of needle wales is disposed at an angle to and are meshed or interlaced with another series of needle wales.

The type of knitted fabric to which this invention refers is that known as ribbed fabric having needle wales on both faces formed by drawing loops in opposite directions, such fabric being distinguished from plain or unribbed fabric having needle wales on one face only formed by drawing all loops in the same direction, and it will therefore be appreciated that in a ribbed fabric certain of the stitches are drawn in an opposite direction to the remainder.

In another particular construction the fabric in accordance with this invention is composed of two series of mutual loops of opposite sense or direction formed from a common thread or threads traversing the entire circumference of the fabric and producing spaced needle wales on both faces, together with a third series of stitches of one sense

or direction occupying the sinker wales on one face so as to form a solid face, the needle wales constituted by one series of mutual loops extending at an angle to the needle wales on the opposite face.

In one method of producing fabric in accordance with this invention, a circular knitting machine may be employed having two sets of needles carried respectively by a cylinder and a dial arranged concentrically with and internally of the cylinder, cams being associated with the two carriers for coating with the needles to draw and form thread loops from one or more thread feeds. Instead of, as is the present practice, providing an equal number of needles in each carrier one carrier is provided with a greater number of needles than the other and means are associated for providing relative rotary movement between the two needle carriers in such a manner that at each revolution of the machine there will always be a point or predetermined number of points at which a needle of the one set is located between two needles of the other set, that is to say, a position for cam operation, yarn feed and mutual stitch formation; in other words the relative positions of any pair of needles comprising one needle of each carrier will always be the same at a fixed point or a predetermined number of fixed points at any given time, the relative rotary movement between the two needle carriers causing successive needles gradually to assume the position of such pair as they approach the said fixed point or points, and gradually diverging from such position as they recede from the fixed point or points.

In this way a fabric is formed comprising two series of needle wales one on each face, the one series of wales, i. e. the wales on one face, being caused to extend at an incline or angle to the other series on the opposite face.

It will be appreciated that if the continuous relative displacement of the two needle carriers is at the rate of one stitch of displacement per horizontal row or course of stitches, and the entire circumference is traversed by the component thread or threads of the fabric, the needle wales on one face will each be made up of a succession of stitches from the

same needle which will mesh successively with loops or stitches formed from a succession of needles on the opposite face.

For the purpose of more fully describing the nature of this invention reference will now be made to the accompanying drawings, wherein:—

Figure 1 illustrates a portion of shogged rib fabric.

Figure 2 shows the theoretical construction of the fabric in Figure 1.

Figure 3 illustrates a portion of shogged rib fabric produced from three sets of needles while in

Figure 4 is shown the theoretical construction of such fabric.

Referring now to Figures 1 and 2, C indicates the knitted loops formed on the cylinder needles and D those formed on the dial needles, and it will clearly be seen by reference to Figure 2 that by shogging the dial relatively to the cylinder to the extent of one needle space at each revolution, i. e. course, the knitted loops D are shogged or drawn across the loops C and successive loops D become knitted in between successive pairs of loops C around the fabric at successive courses. When, however, the customary tension is applied to the fabric the inclination assumed by the needle wales produced on the dial needles becomes shared by those produced on the cylinder needles, thus causing the stitches C of the cylinder needle wales on one face of the fabric to become inclined in an opposite direction to, and to an approximately equal extent as, the stitches D of the dial needle wales on the opposite face of the fabric.

In Figures 3 and 4 is shown a fabric produced by needles operating in three carriers, e. g., a cylinder, internal dial and external dial, the knitted loops produced by the cylinder and internal dial needles being drawn in opposite directions so as to form spaced needle wales on both faces of the fabric, and the external dial needles producing plain stitches which occupy the sinker wales on one face, i. e. the front face, so as to fill in said sinker wales and produce a solid face.

The needles in the internal and external dials are actually disposed opposite to each other, i. e. in radial alignment, but in order to facilitate a clear understanding of the mode of construction and to avoid confusion, the fabric has been drawn in Figures 3 and 4 as though the needles of the two dials are laterally spaced. C designates the knitted loops produced by the cylinder needles, DI those produced by the internal dial needles, and DE those produced by the external dial needles.

The cylinder needles take thread and knit at each course, and such needles may on alternate courses combine with the internal dial needles to produce ribbed fabric and on the remaining alternate courses with the ex-

ternal dial needles to make plain fabric. In the construction illustrated in Figures 3 and 4 both dials are shogged in opposite directions. In Figure 4 is shown the dial needle stitches shogged relatively to the cylinder needle stitches to the extent of one full needle space in each successive course, but it will be appreciated that in the actual fabric produced, the tension on the yarn causes the cylinder needle stitches to be drawn at an angle by the dial stitches as shown in Figure 3.

Where ribbed fabric is produced by the employment of two sets of needles only, the knitting may be effected on alternate needles or on alternate groups of needles in each set at each thread feed, and the shogging regulated accordingly. In this type of fabric two or more threads must be employed and the web knitted by one or more threads becomes interlocked with the web knitted by the remaining thread or threads.

A characteristic feature of the fabric produced in accordance with this invention is that in all its forms it may be regular and continuous in construction throughout its entire circumference that is to say, whatever patterned effect is produced in the stitch formation such effect is repeated throughout the whole circumferential area of the fabric. For example, if for the purpose of a patterning effect the grouping of the needles is varied, the variation may be continuous throughout the whole area of the fabric; and whereas fabrics have hitherto been produced on warp knitting machines in which the stitches of two sets of stitches are shogged or displaced laterally, it has not hitherto been practicable to produce circular or tubular fabrics with shogged stitches from one or comparatively few threads in relation to the number of needles and in which the shogging is continuous throughout the entire circumference of the fabric.

A machine constructed and adapted to produce the fabric herein claimed is described and claimed in an application filed by me concurrently herewith, and bearing Ser. No. 371,562, which application has since matured into Patent No. 1,817,566, dated August 4, 1931.

I claim:—

1. A tubular knitted fabric comprising two series of mutual or intermeshing loops or stitches, the stitches of one of said series being drawn in an opposite direction to the stitches of the other series, said two series being produced from common thread or threads and forming spaced needle wales on both faces of the fabric, and a third series of stitches occupying the sinker wales on one face of the fabric and the series of stitches on one face of the fabric extending at an angle to the series of stitches on the opposite face of the fabric, each of the series of stitches

being of uniform structure throughout without break or gap.

2. A tubular knitted fabric composed of two series of interlacing or intermeshing stitches drawn in mutually opposite directions, the stitches appertaining to each series extending progressively and continuously and without break or gap in the same direction in a spiral manner in relation to the fabric, and the two series of stitches being disposed at an angle to each other.
- 5 3. A tubular knitted fabric formed of two groups of loops, one group being drawn in the opposite direction to the other group to form a ribbed fabric, wherein all the loops of one group incline in the same direction in relation to the length of the fabric to constitute continuously extending diagonal stitch wales the loops of which cross the loops belonging to the other group.
- 10 4. A tubular knitted fabric formed of at least two groups of loops, the loops of one group being drawn in the opposite direction to the loops of another group to form a ribbed fabric wherein all the loops of one group are drawn obliquely to form a series of continuous diagonal stitch wales, while the loops of another group extend obliquely in the opposite direction to form a further series of continuous diagonal stitch wales intersecting with the first mentioned stitch wales.
- 15 5. A tubular knitted fabric formed of at least two groups of loops of which one group is drawn in one direction and another group in the opposite direction to form a ribbed fabric, wherein all the loops of one group are drawn obliquely to form a series of continuous spiral stitch wales on one face of the fabric, the loops of another group drawn in the opposite direction all inclining obliquely in the opposite direction to the first group to form a further series of continuous spiral stitch wales on the other face of the fabric and intersecting the first series of stitch
- 20 45 wales.
6. A tubular knitted fabric formed of two groups of loops, one of which is drawn in one direction and another of which is drawn in the opposite direction to form a ribbed fabric and the third group of loops occupying the sinker wales of one face to give the appearance of a plain unribbed fabric on that face, wherein the loops of one group are all drawn obliquely to form a series of spirally extending continuous stitch wales on one face of the fabric, the loops of the group drawn in the opposite direction being all inclined obliquely in the opposite direction to the first group to form a further series of spirally extending continuous stitch wales on the opposite face of the fabric intersecting with the first series and the third group of loops occupying the spiral sinker wales between the spiral stitch wales on one face of the fabric.
